UNITED STATES PATENT OFFICE.

HARRIET BROWN, OF WOONSOCKET, RHODE ISLAND.

FOUNTAIN-BRUSH.

SPECIFICATION forming part of Letters Patent No. 722,281, dated March 10, 1903.

Application filed December 28, 1902. Serial No. 136,666. (No model.)

To all whom it may concern:

Be it known that I, HARRIET BROWN, a subject of the King of Great Britain, residing at Woonsocket, in the county of Providence and

5 State of Rhode Island, have invented new and useful Improvements in Fountain-Brushes, of which the following is a specification.

10 My invention relates to fountain-brushes, and has for its object to provide a device through the medium of which a stove may be quickly and easily blackened and polished, and this without liability of the operator soiling her hands or getting blacking on her clothes.

15 With the foregoing in mind the invention will be fully understood from the following description and claims when taken in connection with the accompanying drawings, in which—

20 Figure 1 is a longitudinal vertical section of a device constituting the preferred embodiment of my invention; Fig. 2, a transverse section taken at right angles to Fig. 1 and in the plane indicated by the line 2 2 of 25 said figure, and Fig. 3 a detail horizontal section taken in the plane indicated by the line 3 3 of Fig. 1.

25 Similar letters of reference designate corresponding parts in all of the views of the drawings, referring to which—

30 A is the hollow body or reservoir of my improved device, which is preferably of sheet metal and has a filling-opening *a*, normally closed by a screw-cap *b*; B, a brush secured 35 to the body A at the under side thereof; C, a crank-shaft journaled in a sleeve *c*, carried by the cap *b* and removably stepped in a socket *d*, fixed on the bottom of the body; D 40 D, dasher-blades fixed on the shaft within the body; E E, vertically-disposed discharge-conduits extending through the bottom of the body; F, a valve connected by spring-strips *G* to the bottom of the body and normally resting over and closing the upper ends 45 of the conduits E; H H, stems connected to the valve F, extending downwardly through the conduits E and having hooks *e* at their lower ends, and I I daubers, of cotton-waste or other suitable material, held on the stems 50 H by the hooks thereof.

While I prefer to employ two discharge-conduits, two stems connected to and de-

pending from the valve, and two daubers, it is obvious that but one of each may be employed without involving a departure from 55 the scope of my invention.

In practice the ingredients necessary to make liquid blacking are placed in the body A through the opening *a*, after which the opening is closed and the shaft C is rotated, 60 so as to thoroughly mix the ingredients. With this done the device is ready for use. In using the device the end of the body over the daubers I is pressed downwardly, when in virtue of the valve being connected to the 65 daubers the valve will be opened and liquid blacking permitted to pass down through the conduits E and on the daubers. When the daubers are supplied with blacking to the extent desired, such pressure is removed to permit 70 the springs to close the valves, after which the blacking is spread over a stove through the medium of the daubers and the stove is polished through the medium of the brush B. Incident to the blacking and polishing of the stove the valve is opened in the manner described whenever it is necessary to supply the daubers with blacking.

75 It will be readily appreciated from the foregoing that with my improved device a woman is enabled to mix the blacking and quickly and easily blacken and polish a stove without liability of soiling her hands or clothes, which is a desideratum.

80 While I prefer to mix the ingredients entering into blacking in the body A, as described, it is obvious that prepared blacking may be placed in the body and applied to a stove through the medium of my improvements without departure from the scope of 85 my invention. In either case it will be observed that the agitator will enable the operator to keep the blacking in a liquid and well-mixed state.

85 The agitator—*i. e.*, the shaft C and its appendages—is preferably removable from the body in order to facilitate cleaning of the device when necessary.

90 I have entered into a detailed description of the construction and relative arrangement of the parts embraced in the present and preferred embodiment of my invention in order to impart a full, clear, and exact understanding of the same. I do not desire, however,

to be understood as confining myself to such specific construction and arrangement of parts, as such changes or modifications may be made in practice as fairly fall within the scope of my invention as claimed.

Having described my invention, what I claim, and desire to secure by Letters Patent, is—

1. A device for blackening and polishing stoves comprising a hollow body having a discharge-passage in its bottom, a valve for controlling said passage, a dauber connected with the valve and arranged below the bottom of the body and the discharge-passage in said bottom, and a brush carried by the body and arranged below the bottom thereof at the side of the dauber.

2. A device for blackening and polishing stoves comprising a hollow body having a discharge-passage in its bottom, a valve for controlling said passage, a stem connected to the valve and extending through the discharge-passage, and having an upwardly-directed hook at its lower end, a dauber arranged on said hook, and a brush carried by the body and arranged below the bottom thereof at the side of the dauber.

3. A device for the purpose described comprising a hollow body having discharge-passages in its bottom, a valve-strip arranged

over said passages, spring-strips connecting said valve-strip and the body, stems extending from the valve-strip through the passages and having outwardly-directed hooks disposed below the body, and daubers held on the stems by the hooks thereof.

4. The device described comprising a hollow body having discharge-passages in its bottom, and also having a filling-opening in its top, and a removable cap closing the same, a shaft journaled in the cap and in a bearing at the bottom of the body; said shaft being equipped with agitating means, and being removable with the cap, a valve-strip arranged over the discharge-passages, spring-strips connecting the valve-strip and the body, and disposed at opposite sides of the shaft, depending stems extending from the valve-strip and through the discharge-passages, daubers carried by said stems, and a brush arranged at the under side of the body, and connected thereto.

In testimony whereof I have hereunto set my hand in presence of two subscribing witnesses.

HARRIET ^{her} BROWN.
